Francis A. Jacobs Inventor.

By Wm. Day Clarke &
Carpenter his Atty.

UNITED STATES PATENT OFFICE.

FRANCIS A. JACOBS, OF WARREN, OHIO, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed October 14, 1924. Serial No. 743,520.

This invention relates in general to improvements in freight car roofs and more particularly to improvements in the class of car roofs usually designated as "outside metal roofs," which outside metal roof is movably or flexibly positioned on the car so as to cover the wooden sheathing or inside wooden roof of the car; and objects of the invention are the provision of a metallic roof capable of movement in harmony with the motion of the car without the necessity of providing mullions to prevent the roof from shifting; the provision of anchors for such car roofs which are not exposed to the elements and which are arranged to hold the sheets from upward movement and also from too great longitudinal movement; the provision of a roof which is capable of simple manufacture at a reasonable cost and which can be readily applied on the car without the necessity of specially skilled workmen and which when so applied will be water-tight and not require frequent repair and replacement; and such other objects and advantages of the invention as are found to obtain in the structure hereinafter set forth and claimed.

In the accompanying drawings forming a part of this specification, and showing, for purposes of exemplification, a preferred form and manner in which the invention may be embodied and practiced, but without limiting the claimed invention specifically to such illustrative instance or instances:

Figure 1 is a top plan view of a car roof embodying the invention, parts being broken away for better illustration.

Figure 2 is a top plan view of a portion of a car roof at the eaves edge of the side seam caps, showing the relative position of the parts.

Fig. 3 is a vertical cross-section taken on the line 3-3 of Fig. 2.

Fig. 4 is a vertical cross-section taken on the line 4-4 of Fig. 2.

Fig. 5 is a vertical cross section taken on the line 5-5 of Fig. 2.

Fig. 6 is a top plan view of a roof sheet anchor.

Fig. 7 is a side elevational view of the same.

Fig. 8 is a vertical cross-section taken on the line 8-8 of Fig. 6.

Fig. 9 is a vertical cross-section taken on the line 9-9 of Fig. 1.

On the drawing 10 indicates the wooden side plates that extend longitudinally of the car and 11 is the inside wooden roof sheathing which terminates at the eaves flush with the outer face of the side plates. 12 is the side sheathing of the car, the upper edge of which is flush with the upper surface of the wooden roof sheathing at the eaves. At each eaves edge the roof sheathing is gained out at 13 to receive a metal flashing 14 whose inner edge terminates in an upwardly projecting open return bent hook 15 whose upper surface is below the plane of the top of the gained roof sheathing and this flashing is flanged at its other end, which flange 16 depends over the eaves edge of the roof and is secured thereto. Roof sheets 17 are disposed on opposite sides of the ridge, said roof sheets having inverted U-shaped ridge flanges 18 lapped one over the other and side flanges 19, said side flanges 19 consisting of an upwardly extending inwardly inclined portion 20 terminating in a downwardly extending portion 21 spaced from said portion 20 and also spaced from the main body of the roof sheet 22.

At the eaves edge the roof sheets are bent under at 23 and then inwardly at 24 and the inner edge of the portion 24 is bent upwardly at 25 to form a return bent hook 26 spaced from the portion 24. These portions 23, 24, 25 and 26 form a lateral stiffening roll for the eaves edge of the roof sheets, and within the roll there is provided a locking strip 27 which extends outwardly from each side of the roof sheet at 28 and the extensions 28 are bent upwardly at 29. If desired, these locking strips need not extend throughout the length of the lateral stiffening roll, but may consist of short pieces crimped or otherwise secured to only the side edges of the roof sheets.

Roof anchors 30 are provided, in the present instance, secured on the flashing 14 at the eaves edge of the car, one between the sides of each two adjacent roof sheets. These anchors consist of a top web 31 having depending and inwardly inclined

sides 32 spaced from each other to provide a space 33 and said sides terminate in outwardly extending flanges 34 spaced from each other, which flanges 34 may be considered the main body of the anchor as they support the sides 32 and web 31 and are secured to the roof sheathing by means passing through the apertures 35 therein. One end of each of said flanges 34 is bent 10 downwardly over the edge of the roof forming depending flanges 36 which are secured there to the side of the car by nails or other suitable means 37. The lower ends of the sides 32 are cut away to provide slots 38 through which the extensions 28 pass and the upwardly bent portion 29 of the locking strips are thereby loosely confined within the space 33 so that the roof sheets may partake of proper movement and yet be effectively held down on the roof sheathing and prevented from shifting.

A plate 39 is rigidly secured as by welding 39' to the top surface of said flanges 34 of said anchor, said plate covering the space 23 between the flanges 34 beneath the slots 38 and said plate also has at its outer end a tongue 40 which may be bent up to secure a side seam cap in place. Side seam caps 41 extend from ridge to eaves, said caps being of substantially tubular form and having curved sides 42 inwardly turned at their lower ends and terminating in upwardly extending flanges 43 spaced from each other and from the sides 42 and when assembled 30 on a roof, said flanges 43 are arranged in the spaces provided between the portions 20 and 21 of the side flanges 19 of the roof sheets. These seam caps, as shown, enclose the anchors that are secured at the eaves 40 between the sides of adjacent roof sheets, and as they are not connected with the anchors, the anchors may be positioned on the roof sheathing before the seam caps are applied and the anchors may and do hold the roof sheets down independently of the seam caps. The eaves ends of the side seam caps are closed by bending the top and sides of the seam cap one over the other as shown in Fig. 5. After the seam caps are arranged 50 in place on the roof, the tongues 40 are bent up over the end 43' of the caps which holds the cap in position. The ridge ends of the roof sheets are capped by inverted U-shaped caps 44 having outwardly extending flanges 45 arranged over the ridge edges of adjacent roof sheets disposed on opposite sides of the ridge. From the foregoing it will be apparent that the roof sheets are securely held 55 down in place in weathertight condition without requiring wooden mullions or outside clips of any sort.

The ridge ends 46 of the side seam caps 41 are lapped at 47 and are secured together and to the wooden roof sheathing, as shown in Fig. 9, by a bolt 48 which passes through

the usual running board saddle 49, inverted U-shaped ridge cap 44, lapped ridge ends 46 of the side seam caps 41, wooden roof sheathing 11 and longitudinally extending ridge pole 51.

The invention is hereinabove set forth as embodied in a particular form of construction but may be variously embodied within the scope of the claims hereinafter made.

I claim:

1. In a car roof, in combination: roof sheathing, a flashing secured on said sheathing, roof sheets disposed on opposite sides of the ridge of the roof, said sheets having side flanges extending from the ridge to a point short of the eaves edge of the roof, the eaves edges of said sheets terminating in a return underbent portion spaced from the main body of the sheet, a locking strip positioned in the space defined by said return underbent portion of the sheet and projecting upwardly between the edges of adjacent sheets, anchors secured at the eaves edges of the roof between the sides of adjacent roof sheets, said anchors having upwardly bent portions providing a space, said last named portions being connected by a top web and cut away at their lower ends to provide slots through which the locking strips extend, the upwardly bent portions of the said strips terminating in the space provided by the bent portions of the anchors, seam caps enclosing the adjacent side flanges and adjacent roof sheets and the anchor therebetween, and a flashing and holding piece secured to the anchors and having a portion adapted to prevent outward movement of the seam caps.

2. In a car roof, in combination: a flashing secured to said roof and having a portion depending over the sides of the car, said flashing extending throughout the length of the roof; roof sheets disposed on opposite sides of the ridge; ridge caps of inverted channel form arranged over the edges of roof sheets disposed on opposite sides of the ridge; said roof sheets having side flanges, the eaves edges of said roof sheets terminating in a return underbent portion spaced from the main body of the sheet thereabove, a locking strip extending throughout the space provided between the main body of the sheet and the return underbent portion, each locking strip extending beyond the side of the sheet and then bent upwardly; anchors secured at the eaves edge of the roof between the sides of adjacent roof sheets, said anchors having spaced flanges depending over the side of the car and secured thereon and inwardly extending spaced body portions resting on said flashing, the adjacent sides of said body portions extending upwardly and providing a space, said upwardly extending portions being connected together at their upper ends, a por-

- tion of said upwardly extending portions being cut away at the lower ends to provide slots through which the locking strips extend and the upwardly bent portions of said locking strips being arranged in the space provided between the adjacent upwardly extending portions of said anchors, an anchor plate extending over the body portions of said anchors and covering the space between said body portions beneath the slot, and seam caps enclosing the sides of adjacent roof sheets and the anchor therebetween and a portion of said anchor plate being bent up to hold said seam cap.
3. In a car roof, in combination: roof sheathing; a flashing secured on said sheathing at the eaves of the roof; roof sheets disposed on opposite sides of the ridge, said roof sheets having side flanges; an anchor secured at the eaves between the sides of the sheet, said anchor having a slot and also providing a space between portions thereof; the eaves edges of said roof sheets terminating in a return underbent portion spaced from the main body of the sheet thereabove; a locking strip extending at each side of the sheet from the space provided by said return underbent portion, and the adjacent locking strips extending through said anchor slot and having a transversely extending part arranged in the space provided by said anchor and seam caps enclosing the side edges of adjacent roof sheets and the anchor therebetween.
4. In a car roof, in combination: roof sheathing; a flashing arranged on said sheathing at the eaves of the roof, roof sheets having side flanges; an anchor arranged between the sides of adjacent roof sheets, the eaves edges of said roof sheets being bent to provide a lateral stiffening roll, means extending from each side of said roll and arranged in engagement within the adjacent anchor and seam caps enclosing the side edges of adjacent roof sheets and the anchor therebetween.
5. In a car roof, in combination: roof sheets having side flanges, an anchor arranged between adjacent side flanges, the eaves edges of said roof sheets being flanged, means extending from said roof sheets and engaging in said anchor, and seam caps enclosing the side flanges of adjacent roof sheets and said anchor.
6. In a car roof, in combination: roof sheets having side flanges, an anchor arranged between adjacent side flanges, the eaves edges of said roof sheets being flanged, means engaging in roof sheets and said anchor and seam caps enclosing the side flanges of adjacent roof sheets.
7. In a car roof, in combination: roof sheets having side flanges, an anchor arranged between adjacent side flanges, means projecting from each side of the sheets and engaging in said anchor and seam caps enclosing the side flanges of adjacent sheets.
8. In a car roof, in combination: roof sheets, anchors arranged at the sides of said sheets to hold said sheets in position, and means extending between said sheets and anchors for securing said sheets in position.
9. A freight car roof anchor comprising a top web and depending inwardly inclined sides spaced from each other, said sides terminating in outwardly extending flanges, one end of each of said flanges being bent laterally, portions of the lower ends of said sides being cut away to provide slots, and a plate rigidly secured over said flanges and covering the space between said flanges below the slots, said plate having a tongue adapted to be bent transversely.
10. A freight car roof anchor comprising a top web and depending sides inwardly inclined and spaced from each other, said sides terminating in outwardly extending flanges, one end of each of said flanges being bent laterally, portions of the lower ends of said sides being cut away to provide slots.
11. A freight car roof anchor comprising a top web and depending sides each spaced from the other, each of said sides having a slot therein, said sides terminating in outwardly extending flanges, one end of each of said flanges being bent laterally.
12. A freight car roof anchor comprising a top web and depending sides each spaced from the other, each of said sides having a slot therein, said sides terminating in outwardly extending flanges.
13. In a car roof, in combination: roof sheathing; a flashing arranged at the eaves of the roof, roof sheets arranged on said roof, said roof sheets having side flanges, seam caps enclosing the side flanges of adjacent sheets, the eaves edges of said sheets being formed to provide a lateral stiffening roll, locking members extending from each side of the sheets, anchors formed to provide a space in which said locking members extend, said anchors being enclosed by the seam caps.
14. In a car roof, in combination: roof sheets, anchors, and separate members extending from said roof sheets into engagement with said anchors.
15. In a car roof, in combination: roof sheets having side flanges, seam caps respectively enclosing the side flanges of adjoining edges of adjacent sheets, and means enclosed by each of said seam caps for holding said roof sheets down and for maintaining the seam caps in spaced relation to the roof sheets, said means being interposed between the adjoining edges of adjacent sheets and projecting above the side flanges of the sheets.
16. In a car roof, in combination: roof

sheathing, a portion of said sheathing being gained out adjacent the car eaves, a flashing secured in said gained out portion and having a portion depending over the side of the car, roof sheets arranged on said roof, the lower portions of which overlap the upper portions of the flashing and the lower edges of which are bent back on the sheets and locking members extending along said sheets

10 between the same and the bent back portions for holding said sheets in place.

17. In a car roof, in combination: a flashing secured to said roof and having a portion depending over the side edge of said roof, roof sheets disposed on said roof and extending beyond the adjacent edge of said flashing, said roof sheets having lower edge portions bent over on themselves to provide hollow spaces, and locking strips extending 20 through said hollow spaces and secured at their ends for holding the roof sheets in place.

18. In a car roof, in combination: roof sheathing, a portion of said sheathing being gained out along the eaves, a flashing secured in said gained out portion, having

an upper edge bent over on itself and a portion depending over the side of the car, said flashing extending throughout the length of the roof, roofing sheets disposed along said roof with their lower portions extending over the upper portion of said flashing and provided with lower edges bent over on themselves for receiving locking means extending therethrough.

30

35

19. In a car roof, in combination: an anchor secured at the edges of the roof between the sides of adjacent sections of roof covering, said anchor having spaced depending portions secured to the side of the car and body portions resting on the roof of the car, the adjacent sides of said body portions providing a space therebetween, and a holding piece secured over the body portions of the anchor and connecting 40 the same and provided with an extension adapted to be bent upwardly over an end of said anchor.
